No. 11,830

June 29, 1880

UNITED STATES PATENT OFFICE.

JULIUS HERRIET, OF NEW YORK, N. Y., ASSIGNOR TO JAMES CONNER'S SONS, OF SAME PLACE.

DESIGN FOR A FONT OF PRINTING-TYPES.

SPECIFICATION forming part of Design No. 11,830, dated June 29, 1880.

Application filed May 31, 1880. Term of patent 7 years.

To all whom it may concern:

Be it known that I, JULIUS HERRIET, (assignor to JAMES CONNER'S SONS,) of the city, county, and State of New York, have invented 5 and produced a new and original Design for a Font of Printing-Types, of which the following is a specification.

The nature of my design is clearly shown in the accompanying typographic impression; 10 and it consists of a font of printing-types to be used for the formation of ornamental surroundings for printed matter.

The character of the design is Egyptian, and the various members composing the font 15 may be thus described, referring to the figures placed over them:

Nos. 3, 2, and 4 are figures formed by combining the light inclined lines, shaded at intervals, some of the lines longer than others, 20 which figures may be employed for the formation of bodies of water or to form a representation of the sky. In Fig. 2 the inclined lines are placed between two parallel lines.

No. 5 represents an entablature, the face of 25 which is ornamented by a central group of three heavy lines, vertical, or nearly so, with heavy dot terminations above. Upon each side is placed a figure composed of a heavy vertical line with heavy dot termination, from 30 which proceeds, at its base, a heavy horizontal line, joined at its outer end by a short heavy inclined line with heavy curved termination, the angle formed by the meeting of the lines heavily shaded.

Nos. 1, 7, and 6 are representations of sections of the bamboo-cane.

Nos. 13 and 8 are representations of the pyramids.

No. 12 is a representation of an Egyptian yacht. 40

No. 9 is an idealized group of flowers, buds, and leaves.

No. 11 is a tile ornamented upon its face with the shaded base with inclined sides, surmounted by the palm-fruit-like ornaments, between which is placed a flower-like ornament. 45

Nos. 14 and 19 are groups of leaves of the palm-tree.

No. 18 is the capital of a column.

No. 16 is a pilaster having its face ornamented with hieroglyphics. 50

No. 15 is a figure composed of a series of rays, used to represent the sun.

No. 17 represents the base of a column.

Nos. 25 and 26 are representations of the 55 sphinx.

No. 22 is a representation of a statue to be placed upon a building erected from the profits derived from the sale of cereals.

Nos. 20 and 21 together form a figure representing Cleopatra's needle. 60

No. 24 is a representation of a figure mounted upon a camel.

No. 23 is a representation of a statue to be placed upon a building erected from the 65 proceeds derived from metal-working.

Having now set forth my invention, what I claim as new is—

The design for a font of printing-types, substantially as shown and described.

JULIUS HERRIET. [L. S.]

In presence of—

Wm. C. CONNER, Jr.,
MARTIN T. B. CONNER.
